DESIGN FOR A DECORATIVE COMB

Stephen F. Kayn, New York, N. Y., assignor to Injection Moulding Corporation, New York,
N. Y.

Application January 13, 1938, Serial No. 74,273

Term of patent 3½ years

To all whom it may concern:

Be it known that I, Stephen F. Kayn, a citizen of the United States, residing at No. 35 East 9th Street, county of New York, city and State of New York, have invented a new, original, and ornamental Design for a Decorative Comb, of which the following is a specification, reference being had to the accompanying drawing, forming part thereof, in which

I claim:

The ornamental design for a decorative comb, as shown.

STEPHEN F. KAYN.
